UNITED STATES PATENT OFFICE.

CHARLES A. THOMPSON, OF NEW YORK, N. Y.

APPARATUS FOR OBTAINING DUPLICATE COPIES OF WRITINGS.

SPECIFICATION forming part of Letters Patent No. 398,864, dated March 5, 1889.

Application filed June 23, 1887. Serial No. 242,335. (No model.)

To all whom it may concern:

Be it known that I, CHARLES A. THOMPSON, a citizen of the United States of America, and a resident of New York city, in the county 5 and State of New York, have invented certain new and useful Improvements in Apparatus for Obtaining Duplicate Copies of Writings, &c., of which the following is a specification.

10 This invention relates to apparatus for obtaining duplicate copies of writings from a stencil or transfer sheet; and the specific matter of my improvement consists in the improved construction and arrangement or combination of parts hereinafter disclosed, and embodied in specific claims.

15 In the drawings, Figure 1 is a sectional view of an apparatus embodying this invention. Fig. 2 is an end view thereof. Fig. 3 is a face view to show the appearance of the side of the stencil-sheet against which the writing is placed to receive an impression. Fig. 4 is a view hereinafter referred to in connection with the description of the method of producing 20 the transfer or stencil sheet.

25 In the drawings, A represents a press, of which B is a base-plate, C fixed uprights, and D the moving plate guided in grooves or ways *a* in the fixed uprights. The moving plate D 30 is connected, through a pin, *b*, with a strap, *d*, which embraces a disk, E, which is eccentrically hung on a shaft, F, which rotates in bearings in the uprights from the turning of the crank-arm G or otherwise.

35 H represents what is termed the "stencil-sheet," from which to obtain reproductions of the characters thereon and which will now be described. This stencil may be produced in various ways—as, for instance, by placing the 40 sheet H of paper between two sheets, I, impregnated or covered with a composition of divisible aniline or carbon or similar substance, I², with the prepared faces of such sheets against each face of the stencil-sheet H. Then with a 45 pencil or stylus point tracing with sufficient pressure on one of the prepared sheets the characters desired, such characters will be transferred in aniline, &c., on the upper side, *x*, of the sheet H straight forward, and from the 50 under aniline sheet such characters will be transferred on the under side of the sheet H

in the reverse, and such sheet being of a suitable nature to admit will be in and through its thickness impregnated and saturated with the aniline, &c., from side to side thereof, as 55 outlined by such characters. This stencil-sheet is then secured on the lower side of the moving plate D in any suitable manner, having its face presenting the characters in the reverse outward. Paper of suitable nature 60 is placed on the bed B of the press, and the moving plate with the stencil-sheet H is brought against it and will impart therefrom the characters thereon.

It is preferable that the sheets to receive 65 the impressions from the stencil be dampened with a regular and uniform moisture, and in the drawings is shown a means of securing such dampening, to be now described. The paper to receive the impressions is preferably 70 in the form of a strip, J, wound about a roll, K, hung in suitable bearings. It is then passed under a roll, L, the under side of which lies below the surface of water or other liquid in a tank, M, and thence to and between 75 squeezer-rollers N N, and then is carried over the bed or base-plate B of the press in position to receive an impression from the stencil-sheet H when it is forced upon said sheet J. The introduction of the strip of paper J 80 under the roll L in the water and thence through the squeezer-rollers N N sufficiently dampens the strip and equalizes the moisture. The turning by the crank-arm G of the shaft F rotates the eccentric-disk E, and through 85 its strap-connection the plate D, carrying the stencil, is moved downwardly into contact with the base-plate (or with the paper strip thereon) for an instant only, and is carried upwardly again out of such contact. By suitably connecting a belt, O, from the shaft F 90 with feed-rolls P P the paper is drawn off the paper-roll K under the roll L, between the squeezer-rolls N N and over the base-plate B, and after passing through said feed-rolls may 95 be wound upon a take-up roll, R, or otherwise disposed of.

The speed given to the feed-rolls P P is so regulated that the paper will, while the plate D is passing through one upward and downward movement, be caused to travel a distance as great at least as that between the

first line of writing on the stencil-sheet and the last line thereon; and from the above it will be plain that by providing in the plate D of the press a stencil-sheet in which the 5 markation of the characters is sufficiently impregnated with a divisible substance, like aniline, substantially as described, and operating the said plate D through suitable means successively against a sheet of paper lying on 10 the base-plate B of the press, which paper between such successive operations of the press is moved forward, impression after impression is obtained on a strip of paper of one 15 writing or delineation, and the portions of the paper strip J may be separated between the points of boundary of the various impressions, and this production of duplicate copies or impressions may be continued until the supply of aniline in the stencil-sheet has been 20 exhausted.

Obviously, instead of placing the stencil upon the moving plate H and forcing same against the paper resting upon the base-plate B, it is substantially equivalent thereto to 25 place the stencil upon the stationary base-plate B and press the paper firmly against it by the contact thereupon of the moving plate D.

A "stencil" of the character described, instead of being produced by being placed between two prepared sheets and marked by a stylus-point, may be produced by the impression and impact of type-face set up in form or received separately and successively from a type-writer, as customary in printing or writing 30 with a type-writing machine, and in Fig. 5 is shown a stencil-sheet of substantially the same character as hereinbefore described, which consists in a sheet, H, having the characters thereon formed of a series of perforations or abrasions, m—such as may be produced by the proper employment of the well-known electric perforated needle-pen, or by the "cyclostyle pen," as known—behind which sheet is placed a pad, n, impregnated with aniline, &c. When such pad is forced upon the tablet on which the paper rests, the aniline is 45 expressed through the abrasions or perforations in the stencil-sheet and will be imprinted upon the paper sheet, and this form of stencil-sheet is intended to be considered in substance the same as that hereinbefore described in principle and effect.

As the method herein described of preparing the stencil or transfer-sheet (shown in 55 Figs. 3, 4, and 5,) constitutes the subject-matter of a separate and distinct application for a patent filed by me June 18, 1887, under Serial No. 241,638, such matter is not claimed herein.

60 Having thus described my invention, what I claim, and desire to secure by Letters Patent, is—

1. In a manifold printing or transferring apparatus, the combination of a platen reciprocating in suitable ways, an opposite bed-plate, and an imprinting stencil-sheet secured to the face of the platen, as shown and set forth.

2. The combination, with a body or plate having attached thereto a stencil-sheet, substantially such as described, adapted to move up and down in suitable ways, of a liquid-tank and base-plate, and means for conveying a strip of paper, &c., through said liquid-tank and over said base-plate, substantially 75 as described, for the purpose specified.

3. The combination, with a body or plate having attached thereto a stencil-sheet, substantially such as described, adapted to move up and down in relation to a base-plate, of a 80 liquid-tank and squeezer-rolls N N, and means for conveying a strip of paper, &c., through said tank, between said squeezer-rolls and over said base-plate, substantially as described. 85

4. In a manifold printing or transferring apparatus, the combination of a platen reciprocating in suitable ways and having an imprinting stencil-sheet upon its face, an opposite bed-plate, a paper-roller, and a suitable 90 dampening-tank and rollers for dampening and squeezing the strip or web of paper unwound from said roller at one side of the bed-plate, and feed-rollers at the other side of the bed-plate, as shown and set forth. 95

5. In a manifold printing or transferring apparatus, the combination, with a reciprocating platen having an imprinting-sheet upon its face and an opposite bed-plate, of a liquid-tank at one side of the bed, having a guide-roller within it, squeezing-rollers above the tank, and two feed-rollers at the opposite side of the bed-plate bearing against each other, as shown and set forth. 100

6. In a manifold printing or transferring apparatus, the combination of the bed-plate having the tank at one side, the platen reciprocating against the bed in suitable ways, the revolving drive-shaft having the eccentric-disk having its strap pivotally connected to 110 the platen, the paper-roller and guide and squeezing rollers at the tank, and the feed-rollers at the opposite side of the bed having belt-connection to the drive-shaft, as shown and set forth. 115

In testimony that I claim the foregoing as my invention I have signed my name in presence of two witnesses.

CHARLES A. THOMPSON.
